CLAIM

We claim the ornamental design for a device for illumination and imaging of a target, as shown and described.

DESCRIPTION

FIG. 1 is a perspective view of a device for illumination and imaging of a target showing a first embodiment of our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of a device for illumination and imaging of a target showing a second embodiment of our new design;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines in the drawings represent portions of a device for illumination and imaging of a target that form no part of the claimed design.
